UNITED STATES PATENT OFFICE.

ANDREW P. WILLIAMS, OF CHICAGO, ILLINOIS.

CAR END.

1,244,677.

Specification of Letters Patent. Patented Oct. 30, 1917.

Application filed December 24, 1914. Serial No. 878,882.

To all whom it may concern:

Be it known that I, ANDREW P. WILLIAMS, a citizen of the United States, residing at Chicago, in the county of Cook and State 5 of Illinois, have invented certain new and useful Improvements in Car Ends, of which the following is a specification, reference being had therein to the accompanying drawing.

10 My invention relates to railway freight cars, and particularly to the construction of the car end, and it consists in the matters hereinafter described and then pointed out in the appended claim.

15 In the accompanying drawings Figure 1 is a view in elevation of a car end embodying the features of my present invention;

Fig. 2 is a top plan view of the car end;

Fig. 3 is a vertical sectional view taken 20 on the line 3—3 of Fig. 1, and

Fig. 4 is a side view of the parts of Fig. 1.

The sides 9 of the car are constructed of any suitable material, preferably sheet metal plates connected to the car-frame to 25 which my improved car end is secured. In the construction of my car end I employ a plurality of sheet metal plates 10 of sufficient length to extend across the end of the car and of sufficient width when superposed 30 to form the entire end wall of the car, in the present illustration four such plates being employed arranged one above the other.

The adjacent plates are provided near their meeting edges with horizontally disposed 35 stiffening ribs 11 which extend along the length of the plates and are bent outwardly toward the front of the car, each of the ribs being preferably bent at an obtuse angle to its plate and provided with a vertical

40 flange 12 so that these edges are substantially L-shaped in section, and when the plates are assembled the flanges 12 will overlap or telescope as clearly shown in Fig.

45 The overlapping flanges 12 of adjacent plates are beyond or outside of the plane of the body of the plates where they are secured together by rivets 13 as shown, so that the meeting edges of the plates are united to form a substantially outwardly

50 projecting channel beam construction. The outward projection of the horizontal ribs 11 of adjacent plates provides a trough in the inner wall of the car for the rivets so that the contents of the car are protected

55 from injury by the rivets.

The horizontal ribs taper in width or

depth from their centers toward the sides of the car as shown in Fig. 2, their maximum width being at the center of the car end and merging with the plane of the 60 plates near the sides of the car.

The upper edge of the top plate is secured to the usual end-plate of the car body, and the lower edge of the bottom plate is provided with a rearwardly extending 65

flange 14 secured to the usual end sill of the car body or floor, and the ends of each of the plates are provided with angularly ex- 70

tended side flanges 15 to be secured to the car sides, the side flanges being arranged to 75

telescope according as they are associated with the outer or inner vertical flanges 12 of adjacent plates, as shown in the drawings. The top and bottom plates are also 80

provided with angular extensions or ears 16 bent to form to extend more or less along 85

and be secured to the car sides to provide corner bands at the top and bottom of each 90

car corner. The ears are as long as the integral side flanges of their associated top 95

and bottom plates so that they extend rear- 100

wardly beyond the joint of each such plate with an adjacent plate, and by this construction the ears form extended corner-bands 105

that include not only the car-corners but also the joints of the top and bottom plates 110

with adjacent plates, and so eliminate not only the ordinary corner gussets or braces but also the separate angular tie-plates em- 115

ployed at the meeting edges of the top and bottom end-plates with adjacent plates.

By my invention the ribs and overlapping 120

flanges of the plates may be formed by cold 125

pressing when the plates are formed, there- 130

by dispensing with the expensive and time 135

consuming operation of heating the plates 140

and pressing ribs or corrugations in their 145

bodies when so heated, while the channel 150

beam provides a strong bracing or strength- 155

ening construction, which also forms a pro- 160

tecting groove or trough for the rivets, and 165

the angular ears extended around the cor- 170

I claim:

A car-body end constructed of a plurality of superposed metal plates having their meeting edges formed with outwardly pro- 175

jecting horizontal ribs extending length- 180

wise of the plates and provided with over- 185

lapping vertical flanges, the flanges of each 190

pair of adjacent plates being riveted to 195

gether, and angularly extended integral side flanges on the plates, the side flanges of adjacent plates overlapping, and the side flanges of the top and bottom plates extending rearwardly beyond their joints with adjacent plates to form extended ears providing corner-bands in the car-body.

In testimony whereof I affix my signature in presence of two witnesses.

ANDREW P. WILLIAMS.
